UNITED STATES PATENT OFFICE.

JAKOB GROB, OF NEW YORK, N. Y., AND CONRAD KELLER, OF WEEHAWKEN, NEW JERSEY.

CUTTING-OUT MACHINE FOR EMBROIDERIES.

1,085,979.

Specification of Letters Patent.

Patented Feb. 3, 1914.

Application filed March 19, 1912. Serial No. 684,907.

To all whom it may concern:

Be it known that we, JAKOB GROB and CONRAD KELLER, citizens of the Republic of Switzerland, and residing, respectively, at 5 New York, N. Y., and at Weehawken, New Jersey, have invented a new and useful Cutting-Out Machine for Embroiderries, of which the following is a specification.

Our invention relates to machines used to 10 scallop embroiderries and the object of our improvement are, first, to provide a continuously moving and cutting instrument, and second, to afford reliable guiding means for the cutting instrument.

15 We attain these objects by the mechanism illustrated in the accompanying drawing, in which—

Figure 1 is a vertical side elevation of the entire machine; Fig. 2, a detailed top view of 20 the controlling electric contacts; Fig. 3, a detailed plan of the controlling magnets and Fig. 4, shows the embroidery under the guiding and cutting members.

An endless cutting wire or band 1, passes 25 over and is driven by the pulleys 2 and 3. The pulley 2 is rotatably mounted upon the arm 4 which is journaled to the upright 5. A spring 6, fastened to the top of the upright 5 keeps the saw 1 under tension. The 30 pulley 3 is rotatably mounted upon the bracket 7, which is fastened to the upright 5 by screws. A smaller pulley 8 integral with the pulley 3 is driven by the belt 9, which receives its motion through pulley 10.

35 The main driving belt runs over the pulley 10 which is rotatably mounted into the upright 5. The latter is rotatable around its vertical axis, upon the cones 12 and 13. The cone 12 is held in a suitable bearing 14, while 40 the cone 13 is adjusted by the set screw 15 and nut 16 on the bracket 17, the latter being part of the machine frame. It will now be clear that the cutting tool 1 can run continuously in the direction of the arrow and 45 that it can be swung back and forth in an arc upon the axis of the upright 5, for the purpose of following the design 43 Fig. 4, of the embroidery 36 Figs. 1 and 4. The embroidered goods 36 are pulled through the 50 machine by the rollers 40 and 41, and kept stretched between the said rollers and the rollers 38 and 39 by keeping the latter tight in their respective bearings. Between the last named four rollers the table 37 provided

with a slot 44 in the form of an arc, holds 55 the goods 36 against the cutting tool 1.

To swing the cutting tool 1 along the contour 43 of the embroidery a rod 34 is journaled central with the axis of the upright 5 and is provided with a feeler 35 lightly 60 pressing against the embroidery 43 and following its contour, the said pressing being obtained by the spring 48 wound around and fastened to the pivot pin 45 and to the upright 5. Also mounted upon the rod 34 65 there is a contact spring 32 charged with an electric current. This spring 32, when the feeler 35 is swinging back and forth, is, thereby, gliding over the stationary conductor—segments 21'—30' transmitting current to a certain number of the segments, the number of segments actuated upon being always the same, but the individual segments included in that number changing with the movements of the feeler 35. A pair of sectional magnets or solenoids 46, 47 when energized, are actuating a core 19 mounted upon an extension 18 of the upright 5. The magnets 46 and 47 are built up in sections, each one of which is energized individually by 80 one of the segments of the arc 33. It will thus be seen that as many sections of the magnets 46, 47 will be energized, as there are segments on the arc 33 covered by the spring 32. A change in the position of the 85 spring 32 will change the sections energized of the magnets 46 and 47. The core 19 is of such an extension that it covers just the field of so many sections as are energized at one time. Supposing that sections 20, 21, 90 22, 26, 27, 28 and 29 are energized the core will go into the position indicated on the Fig. 2. Moving the spring 32 one segment over the arc 33 will, for instance, energize the sections 23 in addition to the aforementioned sections, but will at the same time de-energize the section 29. This causes the core 19 to swing over to magnet 46 for the width of the section 23, thus turning also the upright 5 and the cutting tool 1. In this way 100 the saw 1 may follow continuously the feeler 35, all the time cutting off the waste 42 along the contour of the embroidery 43. The segments 33 and the magnets 46 and 47 have naturally to be subdivided very finely to 105 guide the saw 1 exactly along the edge of the embroidery, so that no appreciable step by step movements are made.

What we claim and desire to secure by Letters Patent is:

1. A machine for cutting out sheet material comprising in combination means for feeding the material in one direction in a fixed line of travel, an arm swinging across the material in a fixed arc and angular in direction to the direction of the travel of the said material, a revolving endless cutting tool carried by the said swinging arm and electrical means operated by a feeler following raised portions of the said material for the purpose of controlling the swinging of the said swinging arm.
2. In an embroidery cutting out machine, the combination of a cutting endless band, carrying and driving means for the said cutting endless band, means to feed embroidery to the said cutting endless band, means

to swing the said cutting endless band in an arc, feeling mechanism adapted to follow the outlines of the embroideries supplied and means to control the swinging of the said cutting endless band according to the movements of the said feeling mechanism.

3. In an embroidery cutting out machine, the combination of a rotatable standard provided with a plurality of arms carrying pulleys, a cutting endless band carried by the said pulleys, means to rotate the said pulleys, resilient means to keep the said cutting endless band tight and means to rotate the said rotatable standard.

JAKOB GROB.
CONRAD KELLER.
